LOCOMOTIVE BOILER FIREBOX

Bert E. Larson, Park Ridge, Ill., assignor to Locomotive Firebox Company, Chicago, Ill., a corporation of Delaware

Application November 27, 1940, Serial No. 367,350

2 Claims. (Cl. 122—68)

This invention relates to improvements in locomotive boiler fireboxes and it consists of the matters hereinafter described and more particularly pointed out in the appended claims.

One of the objects of the present invention is to provide a locomotive boiler firebox having relative large heating surface so as to increase the water steaming and circulating efficiency of the firebox without increasing its size.

A further object of the invention is to provide a locomotive boiler firebox including a water tube supported fire arch and one or more water steaming and circulating elements disposed entirely within the space above the arch and whereby the arch not only functions for its intended purpose but also protects parts of said elements against direct contact by flames in the firebox.

Also, it is an object of the invention to provide a locomotive boiler firebox which is safe in use even under low water conditions by keeping the crown sheet thereof flooded at all times.

The above mentioned objects of the invention, as well as others, together with the advantages thereof will more fully appear as the specification proceeds to describe the preferred embodiment of the invention.

In the drawing:

Fig. 1 is a longitudinal vertical sectional view through the firebox end of a locomotive boiler embodying the preferred form of the invention.

Fig. 2 is a transverse vertical sectional view through the firebox end of the boiler as taken on the line 2—2 of Fig. 1.

Referring now in detail to that embodiment of the invention illustrated in the accompanying drawing, the locomotive boiler firebox therein shown comprises a fire chamber which extends from the back sheet 5 to the flue sheet 6 and from one to the other of the side sheets 7, the top of the firebox being formed by the crown sheet 8. The lower portion of the flue sheet is made to form the inside throat sheet 9. The usual flues 10 are secured at one end in that part of the flue sheet above the throat sheet.

The firebox is enclosed by a top plate 11 and the usual side plates 12 together with the outside throat sheet 13 and back plate 14, said plates constituting what is commonly called the "wrapper" of the boiler. The back sheet 5 and back plate 14 are formed to provide a fuel door opening 15.

The sheets and plates mentioned define the side water legs 16 and the front and rear water legs 17 and 18 respectively of the boiler, which are closed at their bottom ends by the mud ring

19. The inner sheets defining the firebox and the outer or wrapper sheets are staybolted together in the usual manner.

20—20 indicate conventional arch supporting members in the form of laterally spaced tubes, each fixed at their front ends in the upper portion of the front throat sheet 9. Said tubes extend upwardly and rearwardly from said throat sheet and are fixed at their rear ends in the back sheet 5, at an elevation above the fuel door opening 15. The fire arch, which is indicated as a whole at 21, is constituted by side, center and intermediate rows or courses of brick 22—23 and 24 respectively as appears in Fig. 2. The brick of the center and intermediate rows are supported solely by the arch tubes 20 while the brick of the side rows are supported at their inner sides upon the two outermost arch tubes and are supported at their outer sides upon the side sheets of the firebox in the usual manner.

25 The arch, of course, takes its longitudinal inclination from the arch tubes 20 and the rear end of said arch is disposed at an elevation above that of the door opening 15 and is spaced some distance forwardly of the back sheet 5.

30 The above may be taken as descriptive of a conventional locomotive boiler firebox having a fire arch therein supported by arch tubes. Under fire conditions, the products of combustion are deflected or directed rearwardly to pass over the rear end of the arch on their way to the flues 10 in the flue sheet.

35 According to the present invention I am enabled to increase the water steaming and circulating efficiency, as well as the safety factor of the boiler by providing a plurality of thermic syphons 25 and 26 of such shape and form that they may be disposed in the space between the arch 21 and the crown sheet 8. Said syphons 40 are arranged in a laterally spaced relation and do not obstruct the flame passageway of the firebox above the rear end of the arch.

45 Each syphon includes a flat hollow body 27 having opposed side walls 28—28, front and rear end walls 29 and 30 and a bulged bottom 31. The side walls 28—28 are parallel while the front and rear end walls are disposed at converging angles. All of said walls terminate at the top in a lateral flange 32 that is welded in an elongated opening in the crown sheet. The open top of said body forms the water discharge for the syphon into the boiler water space above the crown sheet.

50 The rear end of the bulged bottom 31 merges into a rounded corner 33 forming a part of the

rear wall of the syphon, while the front end of the bulged bottom is connected to a single inlet neck 34 only. The bulged bottom and the inlet neck are disposed at a more shallow angle of inclination than the arch 20 so that more vertical clearance is provided between the arch and the front end of the syphon body than between the rear end of the arch and the closest point on the syphon body.

The inlet neck 34 of each element is connected by a curved portion 35 to a laterally and outwardly inclined tubular inlet portion 36 having its extremity welded in a collar provided therefor in the associated side sheet of the firebox toward its front end. Said inlet portion takes in water for the associated side water leg, and the passage of said water through said neck 34 and its portions 35 and 36 is always in an upward direction into the syphon body.

It is to be noted that the body of the syphon has a considerable length relatively to its vertical depth and that the rear end of the body has a considerable overhang with respect to the rear end of the arch. With this arrangement of parts, while the space available for the syphons is relatively small, the syphon bodies provide relatively large evaporating surface areas. Thus, the provisions of the syphons described adds materially to the active area of the firebox and increases the steaming and circulating efficiency of the boiler as a whole.

The body and inlet neck of the syphon are disposed high enough above associated parts of the arch to readily permit replacement of such arch brick as may require replacement. Also, the greater part of the bulged bottom 31 of each syphon is protected by the arch from direct flame contact with the fire in the firebox, so that fire checking of the bulge portion of the syphon is materially reduced, if not entirely eliminated.

The present invention also makes it possible readily to convert arch tube fireboxes already in service, into syphon equipped fireboxes and this with relatively small expense. Again, the construction described increases the safety factor of the boiler by keeping the crown sheet of the firebox flooded with water at all times.

While in describing the invention I have referred in detail to the form, arrangement and construction of the parts involved, the same is to be considered as illustrative only, so that I do not wish to be limited thereto, except as may be specifically set forth in the appended claims.

I claim as my invention:

1. In combination with a locomotive type boiler firebox including a crown sheet, side sheets and front and back sheets and an arch tube supported fire arch extending upwardly and rearwardly from a point adjacent the front sheet to a point spaced forwardly of the back sheet, and water circulating and steaming means arranged in the firebox entirely above the arch, said means including a plurality of laterally spaced elements, each having a flat hollow body disposed entirely above the arch and longitudinally of the firebox and having an elongated discharge opening through the crown sheet, the bottom of said body extending upwardly and rearwardly of the firebox and having an intake tube opening through the adjacent side sheet at a point above the front end of the arch, the hollow body of each element having a portion disposed rearwardly of the rear end of the arch.
2. In combination with a locomotive type boiler firebox including a crown sheet, side sheets, a front sheet and a back sheet, arch tubes extending upwardly and rearwardly from a lower portion of the front sheet to an upper portion of the back sheet, means providing a fire arch above the arch tubes and supported at least in part thereon, and which arch terminates at its rear end at a point spaced forwardly of said back sheet and a water steaming and circulating element arranged in the firebox above the arch with the arch interposed between the element and the fire in the firebox, said element including a flat hollow body having opposed side walls, converging front and rear walls and an inclined bottom, said body having a single elongated discharge opening at its top that opens through the crown sheet and an inlet opening at its lower end that communicates with a single opening in the boiler above the fire arch.

BERT E. LARSON.
